The ornamental design for an in-vehicle infotainment device with a touch display that can move up and down, as shown and described.

DESCRIPTION

FIG. 1 is a top front perspective view of an in-vehicle infotainment device with a touch display that can move up and down showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is right side view thereof showing that the touch display of the present in-vehicle infotainment device is lifted up; and,

FIG. 9 is a perspective view thereof showing that the present in-vehicle infotainment device is connected with another device.

The broken lines depict environmental subject matter only and form no part of the claimed design.
